UNITED STATES PATENT OFFICE

EDWARD G. DE FOË, OF OAK PARK, AND CARL BRAMMING, OF CHICAGO, ILLINOIS, ASSIGNEES TO RED BOY, INC., OF CHICAGO, ILLINOIS, A CORPORATION OF DELAWARE

MERCANDISE HOLDER ATTACHABLE TO SERVICE TRAYS

Application filed January 22, 1932. Serial No. 588,075.

Our invention relates to merchandise holders which are attachable to service trays, more particularly trays which are employed at wayside restaurants, barbecue stands, etc. for affording curb service to the occupants of automobiles.

The invention contemplates the provision of merchandise holding and/or displaying devices which are adapted readily to be applied to a tray whereon refreshments are to be served, the said merchandise holding and/or displaying devices being readily removable when they have served their purpose or when the customer has indicated a lack of interest in the merchandise held and displayed by such devices.

The invention is particularly concerned with the construction and arrangement of the instrumentalities whereby the merchandise holding devices are detachably mounted on the tray, and is not particularly concerned with the other structural details of such merchandise holding devices.

In the accompanying drawing illustrating our invention,

Fig. 1 is a perspective view illustrating a preferred form of curb service tray whereon the devices of the present invention are mounted;

Fig. 2 is a perspective of one of the devices embodying the improvements of the present invention;

Fig. 3 is a vertical section which may be regarded as taken on the line 3-3 of Fig. 1 and looking in the direction indicated by the arrows; and

Fig. 4 is a bottom plan view of a corner portion of the tray shown in Fig. 1, this view illustrating how the clamping instrumentalities of the merchandise holding device cooperate with the bottom of the tray.

Similar characters of reference refer to similar parts throughout the several views.

In Figs. 1 and 4 we have illustrated a metal service tray comprising a flat central portion

10 and the upwardly and forwardly curved marginal portion 11, which preferably has a beaded edge, as shown.

The tray shown in the drawing is one embodying the improvements of our copending patent application, Serial No. 588,074, filed January 22, 1932, being a tray having supporting arms 12 which are hinged to the adjacent upturned ends of metal straps 13 which are welded or otherwise secured to the tray transversely of its bottom. The supporting arms 12 are controlled by a bar 14 whereby the arms 12 may be swung to depending positions from the horizontal positions of Fig. 1, and vice versa, and whereby, when the arms are depending, the angularity of the arms to the tray bottom may be adjusted. The purpose of the arms 12 is to support the tray on an automobile door or the like, in the manner fully illustrated and described in our copending application aforesaid.

While the devices of the present invention were particularly designed for use in connection with a curb service tray embodying the improvements mentioned in the last preceding paragraph hereof, it should be understood that the devices of the present invention may be used in connection with any service tray having upwardly and outwardly curved or inclined marginal portions.

Indicated at 15-15 are merchandise holding and displaying devices each comprising a receptacle or receptacles which preferably are formed of sheet metal and may vary in construction, size and shape to accommodate the particular merchandise to be held and displayed thereby. Each of the devices 15, regardless of the characteristics of its merchandise receiving elements, preferably is provided with an elongated bottom element 16.

Riveted, welded or otherwise secured to the bottom 16 of each of the devices 15 is a spaced pair of brackets 17, these brackets being formed of metal strap bent to inverted U

shape—the vertical legs of the brackets carrying integral horizontal flanges or feet indicated at 18 and 19.

Pivoted to the foot 19 of each of the brackets 17 is a clamping element 20, which preferably is in the form of a relatively stiff flat spring pivoted to the bracket foot by a hollow rivet 21. The clamping element 20 preferably is of such a length that its free end 10 may be swung to underlie the foot 18,—the said free end being encased in a soft rubber cushioning sleeve 22.

The vertical legs and the intermediate horizontal leg of each of the U shaped brackets 17, as well as the under surface of its foot 18, preferably are lined with felt or equivalent soft cushioning material indicated at 23 (Fig. 3); such cushioning material conveniently being cemented or glued in position, as shown.

In applying any of the devices 15 to the tray, the elements 20 are swung to the full line position of Fig. 2. The feet 18 of the brackets 17 then are placed on the flat upper surface of the tray, with the legs of the U shaped brackets 17 embracing the inclined marginal portion 11 of the tray. Clamping members 20 then are swung to positions wherein their free cushioned ends underlie and bear tightly against the bottom of the flat portion of the tray. Thus the merchandise holding and displaying devices may be quickly and firmly attached to the tray and may be just as quickly detached therefrom by swinging the elements 20 to their open positions and lifting the devices from the tray.

Each of the devices 15, when attached to the tray, is held very firmly thereon, due to the fact that each of its U shaped brackets 40 17 and the associated clamping element 20 engage the tray at five points, namely, (1) where foot 18 rests on the tray; (2) where the leg of the bracket carrying the foot 18 bears against the marginal portion of the tray; (3) where the horizontal portion of the bracket rests upon the marginal portion of the tray; (4) where the leg of the brackets carrying the foot 19 bears against the bead of the marginal portion of the tray, and (5) 50 where the cushioned extremity of the clamping element 20 bears against the bottom of the tray.

Having thus illustrated and described our invention, what we claim is new and desire to secure by Letters Patent of the United States is:

1. In a merchandise holding and displaying device adapted for application to a service tray comprising a flat central portion and an upwardly and laterally inclined marginal portion, a merchandise receptacle, a pair of spaced attachment brackets carried at the bottom of the receptacle, said brackets being of inverted U shape, one of the vertical

legs of each bracket being provided with a foot adapted to rest on the upper surface of the flat central portion of the tray, and a clamping element pivoted to the other leg of the bracket and adapted to have its free end swung under the flat portion of the tray, in proximity to the aforesaid foot, when the marginal portion of the tray is embraced between the vertical legs of the bracket.

2. In a merchandise holding and displaying device adapted for application to a service tray comprising a flat central portion and an upwardly and laterally inclined marginal portion, a merchandise receptacle, a pair of spaced attachment brackets carried at the bottom of the receptacle, said brackets being of inverted U shape, the vertical legs of the brackets being provided with laterally turned flanges at their lower ends, one of said flanges being adapted to rest on the upper surface of the flat central portion of the tray, and a clamping device, in the form of a flat spring having one end pivoted to the other leg of the brackets and adapted to have its free end swung under and bear against the bottom of the tray when the marginal portion of the tray is embraced by the vertical legs of the bracket.

3. In a merchandise holding and displaying device adapted for application to a service tray comprising a flat central portion and an upwardly and laterally inclined marginal portion, a merchandise receptacle, an attachment bracket of substantially inverted U shape, a foot carried at the lower end of one of the vertical legs of the bracket adapted to rest upon the central flat portion of the tray, and a clamping member having one of its ends pivoted to the other vertical leg of the bracket and adapted to have its free end swung under and bear against the bottom of the tray when the marginal portion of the tray is embraced between the legs of the bracket.

4. In a merchandise holding and displaying device adapted for application to a service tray comprising a central portion and an upwardly extending marginal portion, a merchandise receptacle, means for holding said receptacle on the tray comprising a pair of horizontally spaced downwardly extending legs, horizontal feet carried at the lower extremities of said legs, one of said feet adapted to rest upon the upper surface of the central portion of the tray, and a clamping member having one end pivoted to the other of said feet and adapted to have its free end swung under the bottom of the tray when the marginal portion of the tray is embraced between said legs.

5. In a merchandise holding and displaying device adapted for application to a service tray comprising a flat central portion and an upwardly extending marginal portion, a merchandise receptacle, means for holding

said receptacle on the tray comprising a pair of horizontally spaced vertical legs, a horizontal foot carried at the lower end of one of said legs, said foot being adapted to rest upon the upper surface of the central portion of the tray, and a clamping device pivoted to the other of said legs and adapted to have its free end swung under the bottom of the tray when the marginal portion of the tray is embraced between said legs.

In witness whereof, we hereunto subscribe our names this 18th day of January, 1932.

EDWARD G. DE FOE.
CARL BRAMMING.
